UNITED STATES PATENT OFFICE.

HOWARD M. SMITH, OF RICHMOND, VIRGINIA, ASSIGNOR TO MARIA L. SMITH, OF RICHMOND, VIRGINIA.

FIRE-SHIELD FOR PROSCENIUM-ARCH OPENINGS OF THEATERS.

SPECIFICATION forming part of Letters Patent No. 775,865, dated November 22, 1904.

Application filed February 1, 1904. Serial No. 191,569. (No model.)

To all whom it may concern:

Be it known that I, HOWARD M. SMITH, a citizen of the United States, residing at Richmond, in the county of Henrico and State of Virginia, have invented new and useful Improvements in Fire-Shields for Proscenium-Arch Openings of Theaters, of which the following is a specification.

This invention relates to fireproof shields

- 10 for closing the proscenium-arch openings of theaters; and it has for its object to provide a shield which when moved into position to close the proscenium - arch opening will thoroughly and effectively present an absolutely fireproof barrier between the auditorium of the theater and the stage, the shield being so constructed that it is transparent or opaque, whereby the firemen and theater attendants may intelligently adopt the proper
- 15 precautions and measures for extinguishing or preventing the spread of the fire and whereby in case the lights are extinguished either in the auditorium or on the stage the light from one side or the other of the shield may
- 20 be freely transmitted through the latter, so as to illuminate the surroundings in such manner as to enable the firemen and theater attendants to properly perform their duties and enable the audience to effect their escape.
- 25 To these ends my invention consists in the features and in the construction, combination, and arrangement of parts hereinafter described, and particularly pointed out in the claims following the description, reference
- 30 being had to the accompanying drawings, forming a part of this specification, wherein—

Figure 1 is a view in elevation of my improved fire-shield. Fig. 2 is a horizontal sectional view taken on the line 2 2 of Fig. 1, and

40 Fig. 3 is a vertical sectional view taken on the line 3 3 of Fig. 1.

Before proceeding to describe my invention in detail I deem it proper to preface such description with the statement that I do not 45 wish to be understood as confining myself to a drop shield or curtain or to the specific construction of the frame forming a part of the shield, for the shield may be arranged so as to drop down across the proscenium-arch open-

ing from the flies above, or it may be made in 50 the manner of a pair of sliding doors, which may be arranged to slide from opposite sides of the stage, or it may be movable in any suitable manner, provided the shield may be readily moved into place to close the proscenium- 55 arch opening so as to interpose an effective fireproof barrier between the auditorium and the stage.

In the drawings forming a part of this specification, however, I have illustrated one simple embodiment of my invention, which I will now proceed to describe in detail.

Referring to the drawings, the numeral 1 indicates the stage of the theater, 2 the arched roof of the proscenium opening, and 3 vertical guides arranged on each side of the proscenium opening and having the contour of a trough in cross-section, the shield being embraced by and vertically movable in said trough-shaped guides. The top of the curtain 70 is provided with any suitable suspension device—such, for example, as a bail 4—by means of which the bail may be raised up among the flies when the shield is not in use and by means of which it may be lowered so as to 75 close the proscenium-arch opening when it is desired to interpose a fireproof barrier between the auditorium and the stage. The shield comprises two skeleton frames, each preferably consisting of a number of metal 80 bars or strips 5, which intersect each other at right angles, as shown, the intersecting portions of said strips or bars being rigidly connected together by stove-bolts 6—that is to say, the intersecting portions of each of 85 said frames and the two frames themselves are connected together with the stove-bolts 6, which pass through the intersecting portions of both of said frames. By constructing the frames in the manner shown and described 90 the shield comprises a large number of panels, each closed by a pane of mica 7, the mica panes being clamped between the two curtain-frames.

To the lower edge of the shield is attached 95 a tubular rib 8, comprising a strip of metal bent into substantially cylindrical shape and provided at its meeting edges with two up-

wardly-projecting flanges 9, said flanges embracing the lower edge of the shield and rigidly attached thereto by bolts 10. The tubular rib is compactly filled with a packing composed of comminuted or powdered mica and asbestos. The rib thus constructed affords great rigidity to the shield, and owing to its fireproof qualities and its low conductivity as a heat-conducting medium will effectually resist the action of heated currents of air and flame which seek to gain egress underneath the shield.

In the event of a conflagration taking place upon the stage of the theater it is only necessary to move the shield into position across the proscenium-arch opening, when an absolutely fireproof barrier will be interposed between the stage and the auditorium, and the shield being formed of mica said shield will be transparent, thereby permitting the firemen and theater attendants to intelligently direct their efforts to prevent the spread of the conflagration or to extinguish the same, and at the same time it will permit of the transmission of light through the shield, so that in the event of the lights being extinguished either in the auditorium or among the scenery the actors or audience will have ample illumination to effect their escape in safety. Furthermore, it has proven a source of danger in the employment of the ordinary asbestos curtains now in general use that they are subjected to the action of hot currents of air in such manner that at times the curtain is blown away at the sides or edges from the proscenium-arch opening, thereby permitting the passage of flames, gases, and products of combustion. By means of my improved shield, however,

such a result is rendered impossible, as the shield is rigid in every part, and after it has been moved in position to close the proscenium-arch opening no amount of heat short of that sufficient to melt or fuse the steel framework of the shield can operate to effect the most minute passage-way for the escape of flames, gases, hot air, or products of combustion.

Having described my invention, what I claim is—

1. A fireproof screen for the proscenium-arch openings of theaters, comprising a rigid frame, and a plurality of mica panes supported by said frame, substantially as described. 50

2. A fire-shield for the proscenium-arch openings of theaters, comprising a rigid frame, a plurality of transparent fireproof panes fitted in said frame, a tubular rib attached to the bottom of said frame, and a filling of comminuted asbestos and mica in said tubular rib, substantially as described. 55 60

3. A fireproof shield for the proscenium-arch openings of theaters, comprising two frames each consisting of intersecting metallic bars, panes of mica fitted between said frames, means for fastening said frames together, and means for guiding the fire-shield into place across the proscenium-arch opening, substantially as described. 65

In testimony whereof I have hereunto set my hand in presence of two subscribing witnesses. 70

HOWARD M. SMITH.
